Inventor
Frank Cowan
by Doug & Hague, Atty's.

UNITED STATES PATENT OFFICE.

FRANK COWAN, OF PERRY, IOWA, ASSIGNOR TO NATIONAL SALES COMPANY, OF DES MOINES, IOWA, A CORPORATION OF IOWA.

WRINGER.

Application filed September 30, 1925. Serial No. 59,491.

The object of my invention is to provide a wringer for washing machines of simple, durable and inexpensive construction.

More specifically it is the object of my invention to provide a washing machine wringer which may be constructed entirely of metal and employing improved means whereby the tension between the wringer rolls may be quickly released.

10 A further object is to provide improved means for varying the tension of the rollers, and in connection therewith provide means whereby the position of the tension applying mechanism may be adjusted so the rollers may be adapted to operate on goods of considerable thickness, such as bed covers and the like.

15 A further object is to provide means whereby the material may be more readily fed to the rollers.

A further object is to provide an improved drain board which may be locked in a number of operating positions relative to the main frame.

20 My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved wringer.

Figure 2 is a plan view of the same.

35 Figure 3 is an enlarged detail view showing the release mechanism in one position of its movement.

Figure 4 is an end elevation of my improved wringer.

40 Figure 5 is a detail sectional view taken on the line 5—5 of Figure 1.

Figure 6 is a detail sectional view taken on the line 6—6 of Figure 1.

45 Figure 7 is a detail sectional view taken on the line 7—7 of Figure 1.

Figure 8 is an enlarged, detail, sectional view taken on the line 8—8 of Figure 5.

50 My improved wringer comprises a gear housing 10 having a horizontally arranged frame member 11. The frame member 11 is provided with two pairs of upwardly extending guide bars 12, one pair being mounted at the outer end of said frame member 11, while the other pair is mounted near the

gear casing. Each of the members 12 has its 55 inner face provided with a vertical groove 13, said grooves being designed to slidably receive the roller bearing casings 14. These bearing members are of the ordinary construction. The bearing members 14 are provided with a shaft 15 which carries the wringer roll 16. One end of the shaft 15 is provided with a coupling member 17 which is rotated from a gearing mechanism within the housing 10. The upper ones of the bearings 14 are provided with a shaft 18 having a roller 19. The upper bearings 14 and the said roller 19 are adapted to move freely in a vertical plane toward and from the roller 16.

60 Slidably mounted on the upper ends of each pair of guides 12 is a saddle 20 which rests on the top face of the upper bearing members 14, as clearly shown in Figure 5. Mounted between the bearing members 14 and the end of the rollers 16 and 19 are vertically arranged shield plates 21, each of said plates being provided with a vertical slot 22 designed to receive the shafts 15 and 18. The lower end of the plate 21 is secured 65 to the sides of the lower ends of the members 12 by means of rivets or bolts 23. Each end of the saddle is designed to receive a vertically arranged rod 24, the upper end of each of said rods being provided with an enlarged portion 25 and screw threaded. Said screw threaded portions are mounted in a frame member 26 which extends longitudinally above the top of the roller 19 and is provided at each end with a downwardly 70 extending casing or hood 27. The side members of the hoods 27 are designed to engage the edges of the shield plates 21.

75 The top of the frame member 26 is provided with openings 28 which are designed to slidably receive the upper ends of the shield plates 21. The sides of the hoods 27 are designed to engage the edges of said shield plates and thereby provide means whereby said plates will form guide members 80 for the frame member 26, so the said frame member is free to move vertically.

85 To cause the said member 26 to retain a parallel position relative to the rollers 16 while being moved vertically, I have provided downwardly extending flanges 29 from the member 26 designed to engage the inner faces of the shields 21. Each of the rods

24 is provided with a spring 30 which provides means whereby yieldable pressure may be applied between the member 26 and the saddle 20, and in turn impart a yieldable pressure between the rollers 16 and 19.

For locking the frame member 26 against upward movement and at the same time providing means whereby the pressure between the rollers 16 and 19 may be instantly released, I have pivotally mounted to the central portion of the upper surface of the member 26 a hand lever 31. The central portion of said lever 31 is pivotally connected to oppositely arranged slide bars 32 which are mounted on the upper surface of the member 26 by means of pins or rivets 33 which operate in slots 34. The outer end of each of the bars 32 is provided with a beveled portion 35 designed to engage the under surface of a cross bar 36 across the upper end of the slot 22 of the shield 21. The parts are so arranged that when the members 32 are in alinement with each other and extend longitudinally with the member 26, the beveled edges 35 will rest beneath the lower edge of the bars 36, and thereby provide means for locking the said bar 26 against upward movement with the springs 24 under tension.

30 It will further be seen that if the handle 31 is rotated, the beveled ends 35 will be moved inwardly from beneath the bar 36 which will permit the bars 36 to be elevated and the tension between the rollers 16 and 19 instantly released. The tension between the roller 19 and the bar 26 may be varied by rotating the members 25.

Sometimes it is desirable to support the rollers 16 and 19 apart a slight distance so that thick material, such as bed covers, may be fed between the rollers without injury to the springs 24. This I have accomplished by providing a slot 37 in the upper end of each of the shield plates 21, said slots being 45 designed to receive the beveled ends 35 of the bars 32, which will cause the bar 26 to be supported at a position considerably above its normal working position, and thereby permit a considerable space between the 50 rollers 16 and 19.

By this construction, it will be seen that the wringer may be easily and quickly assembled or taken apart for repairs, if so desired, by simply releasing the latch members 32 and then lifting the arm 26 from the plates 21, the saddle 20 and the springs 24 being retained in position relative to the arm 26 by means of nuts 38 on the lower ends of the said rods 24. The saddle 20 is lifted 60 from the guides 12 at the same time the bar 26 is removed. It will be seen that the rollers with their bearings may be easily removed.

Beneath the roller 16 I have provided a 65 drain board 39 which is pivotally connected

to the inner faces of the plates 21 by means of rivets 40, so that the angle of said drain board may be tilted to either one of two positions for draining water in opposite directions. For retaining the drain board in either of its tilted positions, I have provided hook members 41 pivotally connected to the opposite edges of the lower end of one of the members 21 by means of one of the rivets 23, as clearly shown in Figure 1, said hook members being designed to engage the upper edge of the end plates 42 of the drain board. Said hooks limit the upward movement while the downward movement is limited by the bottom of the drain board, resting on one edge of the frame member 11, as clearly shown in Figure 7.

Mounted adjacent to each side of the roller 16 I have provided a feed plate 43 having at each end an upwardly extending end member 44, the upper end of each of the members 44 being pivotally connected to the plates 21 by means of rivets 45. The plates 43 are inclined downwardly and outwardly. The inner edges of the plates 43 are spaced apart from the roller 16 a slight distance and supported in this position by means of pins or rivets 46, which extend outwardly and rest against the outer edge of the plates 21. By this arrangement it will be seen that the feed plates 43 are free to swing outwardly from the roller 16 a considerable distance, so that in case the roller should become entangled or wound with material no injury will be caused to said feed plates. The feed plates are illustrated in their outer limit of movement by dotted lines in Figure 7, the plates swinging back into position by gravity.

Thus it will be seen I have provided a 105 wringer of simple, durable and inexpensive construction formed in a number of units, said units being easily and quickly assembled, and which may be easily and quickly taken apart for repairs.

It will further be seen that I have provided means whereby the tension between the rollers may be instantly released, and means whereby the upper roller may be adjusted a considerable distance from the lower roller 111 to permit the feeding of heavy material.

It will further be seen that I have provided an improved shield whereby the clothing being operated upon will be held out of engagement with the bearing members of the 120 rollers.

I claim as my invention:

1. A wringer comprising a supporting frame, a pair of wringer rolls, a second frame member movably mounted toward and from the said ringer rolls, means for locking said second frame member at any of a number of predetermined distances from said wringer rolls, means supported between said second frame member and one of said 130

wringer rolls for applying yieldable pressure to said wringer rolls, and means carried by said movable frame member for varying the tension of said yieldable means.

5. 2. A wringer comprising a supporting frame, a pair of wringer rolls, a second frame member movably mounted toward and from the said wringer rolls, means for locking said second frame member at any of a 10 number of predetermined distances from said wringer rolls, means supported between said second frame member and one of said wringer rolls for applying yieldable pressure to said wringer rolls, means carried by 15 said movable frame member for varying the tension of said yieldable means, and means for quickly releasing said locking means.

20 3. A wringer comprising a horizontal support, a pair of upright members connected to said support, a pair of rollers in said upright members, one of which is movable toward and from the other, a frame member slidably mounted on said upright members, 25 yieldable means supported between said slidable frame member and said movable roller, means carried by said slidable frame member for locking it against upward movement, said means comprising a pivoted 30 handle member, and a pair of slide bars arranged in alinement and having their inner ends pivoted directly to said handle member and their outer ends beveled to engage and disengage suitable openings in said 35 upright members.

40 4. A wringer comprising a horizontal support, a pair of upright guide bars, bearing members slidably mounted in said guide bars, a pair of wringer rolls carried by said bearing members, a shield plate between each set of bearing members and the adjacent ends of said rolls, a frame member 45 slidably mounted on the upper ends of said shield plates, means carried by the frame member for imparting yieldable pressure to said rolls, and means for detachably con-

necting said frame member with the shield plates.

5. In a wringer, a support having a pair of upright members, a pair of wringer rolls 50 slidably mounted in said upright members, means for applying yieldable pressure to said rolls, said means including a frame member slidably mounted on said upright members, resilient means between said frame 55 member and said rolls, said upright members being provided with a series of openings, means for locking said bar to said upright members comprising a handle member pivoted on said frame member, a pair 60 of slide bars arranged in alinement and having their inner ends pivoted to said handle member and their outer ends designed to enter a selected one of a series of openings 65 in each of said upright members when the handle member is rotated.

6. A wringer comprising a horizontal frame member, a pair of upright members at each end of said horizontal frame member, an upper and lower bearing member 70 slidably mounted in each pair of said upright members, wringer rolls in said bearings, a saddle slidably mounted on said upright members and resting on the upper ones of said bearing members, each saddle being 75 provided with a vertically and slidably mounted rod having its upper end enlarged and screw threaded, a spring on said rod between said enlarged portion and said saddle portion, said screw threaded portion 80 being mounted in a second frame member arranged parallel with said rollers, said frame member being slidably mounted on a pair of shield plates mounted between said rollers and said bearing members, said 85 shield plates each being provided at its upper end with an opening, slide bars carried by said second frame member, and means for quickly moving said slide bars to engage or disengage the openings in said 90 shield plates.

FRANK COWAN.
